AUTOMATICALLY OPERATIVE MAGNETIC
SEPARATOR

Heinrich Spodig, Dortmund-Wambel, Germany

Application October 16, 1951, Serial No. 251,578

Claims priority, application Germany
December 11, 1950

5 Claims. (Cl. 210—1.5)

1

This invention relates to an automatically operative magnetic separator for flow media of the fluid or of the gaseous or mixed type.

The flow medium may consist of colloidal suspensions or mixtures of non-magnetic substances, such as sand, silica, fine metals with fine magnetizable components, for instance iron, iron oxides and the like.

Automatically operative separator and filter plants based on the use of roller- or disc-shaped permanent magnets are known. In these known installations, use is made of rotatable magnets and interrupted or non-homogeneous fields of force.

The flow media to be separated, such as liquids, are entered into a casing provided with a rotatable magnet; the flow media pass the lower part of the roller and are discharged from the casing, the rotatable magnet intended to separate the magnetizable particles from the flow, which are discharged by means of a stripper and the like.

These known magnetic purifiers and separators do not operate satisfactorily, since a large portion of both the magnetizable and non-magnetizable particles are not separated from the material and particularly liquid flows.

In order to improve the efficiency of these known magnetic separators, they have been combined with mechanical filters; the latter, however, were very rapidly clogged; as a consequence, the flow of the liquid media was dammed in the separators, consequently, it overflowed and caused innundations.

It is the object of the invention to eliminate the above referred to drawbacks of the hitherto customary magnetic separators for fluid and gaseous flow media.

It is a particularly important object of the invention to secure a steady unimpeded flow of the media to be magnetically separated through the separators and the casings, which accommodate the same.

It is another object of the invention to prevent the clogging of the flow media in the separator casings and to eliminate the flooding thereof, if liquid flow media are treated.

It is a further object of the invention to insure a reliable and complete operative contact of the flow media to be magnetically separated with the separator roller or discs.

It is another object of the invention to prevent the reentanglement of separated portions of the treated flow media with fresh or partly treated portions of the charge.

2

It is also an object of the invention to effectuate a smooth unimpeded passage of the flow media through the separator and to effect at the same time a complete separation of the magnetizable and unmagnetic particles.

With these and other objects in view which will become apparent as this specification proceeds, the invention will now be described in the following with reference to several preferred embodiments thereof, without however, in any way restricting the same thereto and with reference to the accompanying drawings illustrating these preferred embodiments.

In the drawings

15 Figs. 1-5 illustrate vertical sectional views of separator casings equipped in conformity with various modifications of the invention;

Figs. 6, 7 show side views of a separating plant; and

Fig. 8 is a plan view thereof.

20 The magnetic separator shown in Fig. 1 comprises an outer casing 1, which is divided by a wall 2 into a larger operating chamber and a smaller secondary or entrance chamber 5, the flow medium to be treated being indicated by arrows.

A bottom opening 3 is provided in wall 2; the charge to be purified passes through this opening from chamber 5 into the lower section of the main chamber 4; after separation in this chamber 4, it is discharged through opening 6. A cover 7 is provided at the top of casing 4.

25 A cylindrical magnetic separator drum is rotatably mounted in the walls 2 and 8 of casing 1 by means of journals 17. This drum is composed of

30 alternate annular magnets 9 and ferromagnetic guide discs 10 in such a manner that the annular magnets or magnet rings 9 bear on both sides of the guide discs 10 with the same polarity N—N or S—S. Therefore, at the periphery of the ferromagnetic guide discs 10 a field of doubly strong

35 polarity results, which short-circuits itself via N—S at the surface of the cylindrical drums. Accordingly at the periphery of the ferromagnetic guide discs 10 and on the entire circumference of the drum, an uninterrupted, outwardly directed, homogeneous magnetic field results.

40 The spaces 11 between the ferromagnetic guide discs 10 may be filled with non-magnetic materials, such as brass, copper, or aluminum, to produce a completely smooth surface of the drum.

45 The annular magnets 9 and the ferromagnetic guide discs 10 are mounted on a non-magnetic shaft 12, which may be replaced by a hollow

50 spindle.

The annular magnets 9 may also be composed of individual segmental bodies of any desired shape and they may have angular, oval or other shapes serving the same purpose as the rings 9.

In order to conduct the flow media to be separated into an optimum reaction range of drum A, bar-shaped projections 13 shaped in conformity with the contours of the drum A are spacedly provided in the lower portion of main chamber 4 at right angles to the direction of the material flow in such a manner that a narrow gap is created therebetween and the drum A. In this manner, the flow medium entering into the main chamber 4 is forced to pass across the bars 13 and to flow directly along the periphery of the drum A through places where the magnetic field has its maximum separating capacity.

The length of the drum and accordingly the number of magnetic stages and the number of bars 13 depend upon the requirements of the individual cases of application.

In the embodiment shown in Fig. 2 and in contradistinction to the above described modification of the invention, air gaps 11 are provided between the ferromagnetic guide discs 10.

A spacing sleeve 14 of non-magnetic material tightly seals the magnetic drum body at a certain distance from the periphery of the guide discs 10, so that a type of rake drum is formed. The guide bars 13 project in this case into the magnetic fields between two ferromagnetic guide discs 10, so that a labyrinth-like separating effect is attained, which is still more effective than the one of the previously described embodiment; this is due to the fact that the particles to be separated are brought nearer to or into the strong magnetic fields of the individual drum stages.

A further embodiment of the invention is illustrated in Fig. 3.

Here the arrangement of the annular magnets or magnet rings 9 and the guide discs 10 is different from those described, in so far as the second, the fourth and further intermediary guide discs 15 are reduced in size and enclosed by the spacing sleeve 14, which latter may be also omitted.

Due to the fact that the size-reduced guide discs 15 are located between the guide discs 10, which have a larger diameter than the magnet rings 9, a particularly strong magnetic field results at the tip of the guide discs 15, which has the tendency to short-circuit itself in the interior of the drum towards the guide discs 10 with the creation of corresponding counter-polarity. In this manner, in the space between the guide discs 10 a powerful magnetic suction field is directly and inwardly created of the circumference of the drum, while on the guide discs 10 themselves, in contradistinction to the magnetic drum of Figs. 1 and 2, no outwardly active magnetic field exists. The guide bars 13 extend into the spaces between the guide discs 10 so that the flow medium to be separated is directly conducted into the powerful suction fields near the center discs 15.

Still another embodiment of the magnetic drum A is illustrated in Fig. 4.

Here, the thickness of the inner sections of the guide discs 10 is increased relative to the annular magnets 9 in order to enlarge the width of the magnetic field stages.

This arrangement basically corresponds to that shown in Fig. 2, where the magnetic fields at the periphery of the ferromagnetic guide discs 10 are outwardly short-circuited via N-S.

In order to create a high-powered magnetic field of limited extension in the interior between the ferromagnetic guide discs 10, additional ferromagnetic annular guide discs 16 are disposed between two ferromagnetic guide discs 10, which guide discs in contradistinction to the discs 10 are not in direct contact with the magnet rings 9.

In conformity with this arrangement, the force lines which otherwise flow outwardly via N-S from the periphery of the ferromagnetic guide discs 10, are forced to pass through the path of least resistance from pole to pole in the interior of the drum and between the ferromagnetic guide discs 10 by way of the ferromagnetic guide ring discs 16.

In this manner, a precisely limited and concentrated magnetic field is created in the interior of the drum A, whereby the separating action is greatly increased and locally limited.

The projecting guide bars 13 are disposed between ferromagnetic guide disc 10 and annular disc 16. In the shown modification, three main separator stages result, of which each is divided into two sub-stages.

25 The number of the three stages may, of course, be increased, or within one stage, a plurality of ferromagnetic annular guide discs 17 may be provided, whereby the labyrinth-like action is further increased.

30 The magnetic drum A may also be constructed from a combination of the previously described embodiment, as shown in Fig. 5.

Here in the first stage of the separator, the embodiment of Fig. 3 and in the following three stages, the one of Fig. 4 is installed in the individual stages.

It is, of course, possible to also select other combinations than the one just described, if this appears to be desirable.

40 The here shown arrangement has the advantage that in the first stage, a large percentage of the flow medium may be treated and discharged, while the rest is processed in the next separator stages.

45 Figs. 6, 7 and 8 show side and plan views of a separating plant built in conformity with Fig. 5.

Numeral 1 denotes the casing box, 5 the entrance chamber, 6 the outlet pipe and 17 a cover. The magnetic drum is driven by a motor 18 over

50 a gear connection 19.

The particles magnetically separated from the flow medium are recovered by the rotating drum and discharged by way of chute 20; this chute is preferably shaped to correspond to the dimensions and the length of the separator drum.

55 It will be apparent to those skilled in the art that the novel principles of the invention disclosed herein in connection with specific exemplification thereof will suggest various other modifications and applications of the same. It is accordingly desired that in construing the breadth of the appended claims, they shall not be limited to the specific exemplification of the invention described herein.

60 Having thus described the invention, what I claim as new and desire to be secured by Letters Patent, is as follows.

1. In a magnetic separator for flow media an outer tubular casing, a non-magnetic outer drum, a permanently magnetic horizontal separator drum composed of annular magnets and circular ferromagnetic guide discs the latter being located between said magnets and extending transversely to the flow direction of the flow media, a center shaft axially extending through

said casing to rotatably support said separator drum, a lateral inlet chamber for said flow media and a bottom passage in said casing for the conduct of said flow media from said inlet chamber into the bottom space between said magnetic drum and said casing, a plurality of ribs upwardly projecting from the bottom of said drum into the entire range of the magnetic fields produced by said permanently magnetic separator drum, said ribs extending in a direction parallel to said guide discs, an outlet for said flow media located at the end of said drum opposite said inlet chamber, said drum being composed of a first and a second portion, the first portion being adjacently located to said inlet chamber and being composed of annular magnets and circular ferromagnetic guide discs having a larger diameter than said annular magnets, the second portion of said drum being composed of annular magnets having a smaller radius than the annular magnets of said first portion of said separator drum, the guide discs extending in a parallel direction to said ribs into said flow media, the ferromagnetic guide discs being disposed between said annular magnets in such a manner that the latter alternately bear against said guide discs on both sides thereof with the same polarity.

2. In a magnetic separator for flow media according to claim 1, the inner portion of the ferromagnetic circular guide discs of the second portion of said separator drum being thickness-increased relative to the outer portions of said guide discs.

3. In a magnetic separator according to claim

5
10
15
20

1, said ferromagnetic guide discs being disposed between said magnets projecting circumferentially beyond the latter, a concentric sleeve of a non-magnetic material spacedly surrounding a part of the annular magnets and fastened to the projecting parts of the adjacent guide discs, additional guide discs between the residual ferromagnetic guide discs ending short of said annular magnets and being fastened to said residual guide discs.

4. In a magnetic separator according to claim 1, annular conductor discs fastened to said non-magnetic outer drum and substantially corresponding in shape to the outer portions of the ferromagnetic guide discs.

5. In a magnetic separator drum according to claim 1, the ribs located in the bottom portion of the same being spaced in the flow direction of the treating media at a gradually reduced mutual distance.
